APPARATUS FOR ELIMINATING ICE FROM WINDSHIELDS

Filed Feb. 4, 1929

FIG. 1.

FIG. 2.

FIG. 3.

FIG. 4.

Cliff R. Otto INVENTOR

BY Loyall J. Miller ATTORNEY

UNITED STATES PATENT OFFICE

CLIFF R. OTTO, OF EDMOND, OKLAHOMA

APPARATUS FOR ELIMINATING ICE FROM WINDSHIELDS

Application filed February 4, 1929. Serial No. 337,512.

My invention relates to apparatus for and method of eliminating ice from the wind-shield of automobiles.

The objects of my invention are to produce a device of the class described which will be new, novel, practical, useful and of utility; which will be economical in construction, installation and operation; which will be removable; which will be easily installed upon any automobile; which will be compact and easily carried; which will accomplish all of the purposes for which it is intended.

There has previously been some attempts made to eliminate the freezing of moisture upon the automobile wind-shield, such as: placing a lighted candle upon the inside of the car and near the wind-shield thereof; and the installation of electrically heated coils and wires adjacent the wind-shield, operating by electricity from the bottom of the car. The use of a burning candle is not a success for night driving, because the light of the candle must necessarily be directly between the driver and the wind-shield. This is dangerous because it obstructs the driver's vision and also because the candle is liable to fall from its position and ignite the clothing of the occupants, or some part of the automobile. It is impractical also because it will burn only in a closed car. The use of heated coils and wires have proven impractical owing to the fact that they use an excessive amount of electrical current, and thus, run down or discharge the battery very quickly. The installation and use of a device of this nature is usually very expensive.

My invention is not operated by electricity and therefore does away with expense of operation which is encountered in electrically heated coils, and the like, and it is not required to be heated. The construction of my device is much cheaper than most methods, and eliminates all danger from fire. It may be removed and carried inside the car when it is not in use. It may be installed for use quickly. The operation thereof is of very little expense.

With these and other objects in view as is to allow the free passage of air into tank

will more fully appear my invention consists in the construction, novel features, and combination of parts hereinafter more fully described, pointed out in the claims hereto appended, and illustrated in the accompanying one-sheet drawing, of which,

Figure 1 is a fragmentary perspective view of the front of an automobile, showing my invention installed thereon; Fig. 2 is a perspective view of the device, showing its relation to wind-shield and wind-shield wiper; Fig. 3 is a sectional view through reservoir; Fig. 4 is an elevational view showing the end of delivery tube positioned against a fragment of wind-shield glass.

Like characters of reference designate like parts in all the figures.

It is understood that various changes in the form, proportion, size, shape, weight and other details of construction, within the scope of my invention may be resorted to without departing from the spirit or broad principle of my invention and without sacrificing any of the advantages thereof; and it is also understood that the drawings are to be interpreted as being illustrative and not restrictive.

A practical embodiment of the invention as illustrated in the drawings includes: A quarter round elongated tank or vessel 1, made of metal or other suitable material, which is mounted on the cross-frame 2, of the top, above the wind-shield of an automobile. This may be required to vary as to shape and size for fitting the front portion of various makes of automobiles. The form I have shown is especially adapted to fit beneath the sun visor 28. Glued or otherwise attached to the vertical back 5 of said tank 1 is felt strip 3, better seen in Fig. 3. Said strip 3 is to protect cross-frame 2 from scratching by tank 1, and may be made of other suitable material than felt, if desired. Tank 1 has bottom 4, vertical back 5, rounding top 6, and ends 7 and 8. Said top 6 has round, flanged opening 9 into which is inserted cork 10 with perforation 11 therethrough. Said opening 9 is for filling vessel 1 with liquid. Said perforation 11 in said cork 10

1 as the liquid contained therein is used therefrom.

Upon the back 5 of said tank 1, and fastened by any means or made integral therewith are supporting hooks 12 and 13. Said supporting hooks 12 and 13 are provided for fitting screw or bolt heads 14 and 15 which are attached at the proper distance apart, into cross-frame 2. Said tank end 7 is provided with round threaded opening adjacent the corner thereof, for receiving short nipple 16. One end of said nipple 16 is threaded to screw into said tank end opening; the other end of said nipple 16 being smooth and not threaded. Fitting over smooth end of said nipple 16 is one end of connecting hose 17. Said hose 17 is made of rubber or other suitable material and fits around said nipple 16 closely enough to allow no leakage of liquid between the two. The other end of said hose 17 fits over pipe 18 in the same manner as hose 17 fits over said nipple 16, allowing no leakage. Said pipe 18 is straight from its end at hose 17 to a point 19, adjacent its other end. At said point 19 said pipe 18 is bent at an obtuse angle as is shown in Figs. 1, 2, and 4. Upon the bent end of said pipe 18 and fitting snugly therearound is delivery hose 20. The loose end of said delivery hose 20 is cut off or terminated at an angle or bevel, better seen in Figs. 2 and 4. The lip 21 of the beveled end of delivery hose 20 touches the wind-shield 22 of the automobile, just above the upper end 23 of wind-shield wiper 24 and is clear of the sweep thereof. Said wind-shield wiper 24 may be of any standard make and design, either hand powered or automatic. Adjacent the middle of said connecting hose 17 is provided screw-clamp pinch cock 25, of known make or design. However, it is preferred that it be provided with an arm or plate for closing the usual opening between the jaws, for better preventing the loss of same from the device. Said hose-clamp pinch cock is for shutting off the gravitational flow of liquid from said tank 1 through said connecting hose 17. At the lower edge of said top cross-frame 2 and the proper distance apart and both within the length of said pipe 18 is provided screw-hooks 26 and 27, for holding said pipe 18 rigidly against said cross-frame 2. It will be seen that the curved top 6 of said tank 1 enables said tank 1 to be installed upon said automobile top cross-frame 2 without the removal of or interference with automobile sun visor 28.

The installation of my invention, it will be seen, merely consists of properly attaching said bolts or screws 14 and 15 and said supporting hooks 26 and 27 to said automobile top cross-frame 2. Then the placing of tank 1 so that it and the entire feed-line thereto attached is supported upon said screws 14 and 15 and said hooks 26 and 27. After tank

1 and the entire feed line thereto attached has been correctly positioned upon their respective supports, pipe 18 is turned in hose 17 so as to bring lip 21 of delivery hose 20 into touch with wind-shield 22. It will be seen in Fig. 4 that only the lip of said hose 20 touches the wind-shield 22 and not the entire beveled end thereof. This is to prevent the hermetical sealing of said hose 20 against the wind-shield 22. Said screw-clamp pinch cock 25 is kept closed at all times when device is not in operation.

In operation said tank 1 is filled with a saturate solution of sodium chloride, and said screw clamp pinch cock 25 is opened slightly to allow the passage of said solution through pipe 18 and delivery hose 20. Said lip 21 of said delivery hose 20 conveys said solution to wind-shield. Said wind-shield wiper 24 spreads said solution over the outside of wind-shield, and thus keeps a portion thereof clear of ice. The flow of said solution to wind-shield may be governed by the tightening or loosening of said screw clamp pinch cock 25. When the device is not in use it may be lifted off said supports 14, 15, 26 and 27 and carried inside of the automobile, or tool chest.

In using this device other liquids than sodium chloride may be used, such as: a saturate solution of calcium chloride; a mixture of alcohol and glycerine; gasoline; or either alcohol or glycerine by themselves; or other suitable liquids. The use of sodium chloride is preferable, however, because salt may be obtained on the road at any store or almost any farmhouse or dwelling. It does not gum up the car as glycerine and the mixture of glycerine and alcohol do. It does not ruin the paint or duco finish of the car as gasoline or alcohol does.

Obviously, the invention is susceptible of embodiment in forms other than that which is illustrated in the accompanying drawings and described herein, and applicable for the uses and purposes other than as detailed, and I therefore consider as my own all such modifications and adaptations and other uses of the form of the device herein described as fairly fall within the scope of my invention.

Having thus described my invention what is claimed and desired to be secured by Letters Patent, is:

1. A device of the class described, comprising a rigid reservoir disposed on the exterior of the front top cross-frame of a motor vehicle, adjacent the front surface of the wind-shield thereof, for housing a suitable liquid, having protruding from one of its lower edges, a short nipple, a suitable pipe adapted to be anchored to said top cross-frame having its outer end turned downwardly, a delivery tube of suitable material adapted at one end to snugly fit the turned

- down portion of said pipe its other end being beveled forming a lip on its lower edge, said lip being adapted to constantly touch the outer surface of said wind-shield, a rubber tubing adapted at one end to snugly fit said short nipple the other end adapted to fit said pipe, a screw-clamp pinch-cock, adapted to fit said rubber tubing and to regulate and stop the flow of liquid therethrough, all and as for the purposes specified.
- 5 2. A device of the class described, comprising a reservoir disposed on the exterior of the front top cross-frame of a motor vehicle, adjacent the front surface of the wind-shield thereof, for housing a suitable liquid, having protruding from one of its lower edges, a short nipple, a suitable pipe adapted to be anchored to said top cross-frame having its outer end turned downwardly, a delivery tube of suitable material adapted at one end to snugly fit the turned down portion of said pipe its other end being beveled forming a lip on its lower edge, said lip being adapted to constantly touch the outer surface of said wind-shield, a rubber tubing adapted at one end to snugly fit said short nipple the other end adapted to fit said pipe, a screw-clamp pinch-cock, adapted to fit said rubber tubing and to regulate and stop the flow of liquid therethrough, all as and for the purposes specified.
